UNITED STATES PATENT OFFICE.

EDWARD I. MOWER, OF CRESSON, PENNSYLVANIA.

RESILIENT WHEEL.

1,240,357.

Specification of Letters Patent. Patented Sept. 18, 1917.

Application filed May 19, 1917. Serial No. 169,733.

To all whom it may concern:

Be it known that I, EDWARD I. MOWER, a citizen of the United States, residing at Cresson, in the county of Cambria and

5 State of Pennsylvania, have invented certain new and useful Improvements in Resilient Wheels, of which the following is a specification, reference being had to the accompanying drawings.

10 This invention relates to certain improvements in resilient wheels and it is an object of the invention to provide a device of this general character for novel and improved means whereby the shocks and jars incidental to travel are substantially entirely absorbed.

15 It is also an object of the invention to provide a device of this general character wherein the wheel is effectively braced to 20 overcome lateral strain.

The invention consists in the details of construction and in the combination and arrangement of the several parts of my improved resilient wheel whereby certain important advantages are attained and the 25 device is rendered simpler, less expensive and otherwise more convenient and advantageous for use, all as will be hereinafter more fully set forth.

30 The novel features of the invention will hereinafter be definitely claimed.

In order that my invention may be the better understood, I will now proceed to describe the same with reference to the accompanying drawings, wherein—

Figure 1 is a fragmentary view in elevation of a wheel constructed in accordance with an embodiment of my invention;

Fig. 2 is an enlarged fragmentary view 40 partly in elevation and partly in section illustrating a pair of bracing members as herein embodied; and

Fig. 3 is an enlarged fragmentary view 45 partly in section and partly in elevation illustrating in detail a connection of an outer end of a spoke with the felly of the wheel as herein disclosed.

As disclosed in the accompanying drawings H denotes the hub of my improved 50 wheel provided with transversely spaced annular flanges 1. Extending between the flanges 1 are the inner end portions of the spokes S which are pivotally held between said flanges 1 through the medium of the 55 pintles or bolts 2. Each of the spokes S

comprises two sections 3 and 4. The section 3 has its outer portion tubular to snugly receive the inner end portion of the section 4. The outer end portion of the section 4 extends within a suitable opening or recess 60 produced in the annular member 6. The outer end portion of the member 4 is also pivotally held to the member 6 through the medium of the bolt or pintle 7. The outer end portion of the section 4 has threaded 65 thereupon the nuts 8 and interposed between the inner nut 8 and the outer end of the co-acting section 3 is an expansible member 9 herein disclosed as a coiled spring encircling the inner end portion of the section 4 and 70 which serves to constantly urge the section 4 outwardly. It is to be understood that the nuts 8 may be adjusted longitudinally of the section 4 to regulate the tension of the expansible member or spring 9 in accordance 75 with the requirements of practice. Intermediate each pair of adjacent spokes S is arranged a pair of bracing members B. Each of the members B comprises two flat sections 10 having their adjacent end portions in overlying relation and pivotally connected as indicated at 11. The opposite end portion of the inner section 10 of each of the members B is pivotally engaged with a pintle or a bolt 12 disposed through the 80 peripheral portions of the flanges 1. It is preferred that the portion of each of the pintles or bolts 12 intermediate the flanges 1 be surrounded by a spacing sleeve 14 so that strength of the hub H is materially increased. The outer end portion of the other section 10 of each of members B is pivotally 85 engaged with the bolt or pintle 15 disposed through the annular member 6.

The member 6 fits snugly within the rim or felly R and is held in applied position in any desired manner but preferably through the medium of the bolts 16 or the like. It is also to be noted from the disclosure in Fig. 2 that the member 6 is of a width less than 90 the space between the flanges 1 so that the members B of each pair are disposed inwardly in divergence so that the wheel structure is effectively braced against lateral strain and to maintain the rim R in proper 95 position relative to the hub H. To further facilitate the function of the members B I find it of advantage to apply to the opposite end portions of each of the bolts 12 intermediate the adjacent end portions of the 100

105 110

members B and the flanges 1 the washers 18. The outer faces of the washers 18 are convex as particularly illustrated in Fig. 2 of the accompanying drawings. This formation of the washers 18 is of material advantage as it prevents such bending of the inner end portions of the brace members B upon relative lateral movement of the rim R and the hub H flexing the members B in a manner which would ultimately result in the fracture of the members B. It is to be understood that any form of tire may be applied to the rim or felly R as the requirements of practice may dictate but it is preferred that a solid tire be employed so that the possibility of punctures, blowouts, or the like are eliminated.

From the foregoing description, it is thought to be obvious that a resilient wheel constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my in-

vention in practice, except as hereinafter claimed.

I claim:

A wheel structure comprising, in combination, a hub, a felly, spokes interposed between the felly and the hub and pivotally engaged therewith, each of said spokes comprising telescopically engaged sections, means co-acting with the sections of each of the spokes for constantly imparting separating movement thereto, brace members positioned between adjacent pairs of spokes, each of said brace members comprising pivotally connected sections, said brace members being arranged in pairs and disposed inwardly in divergence, the outer end portions of the brace members being pivotally engaged with the felly, bolts disposed through the hub and extending beyond opposite sides thereof, the inner ends of the brace members being pivotally engaged with the bolts, and washers arranged upon the bolts and positioned intermediate the brace members and the hub, the faces of the washers adjacent the brace members being convex.

In testimony whereof I hereunto affix my signature in the presence of two witnesses.

EDWARD I. MOWER.

Witnesses:

RAYMOND HOGAN,
H. E. LOWMAN.
